ATTORNEY

UNITED STATES PATENT OFFICE.

LOUIS NEUMANN, OF NEW YORK, N. Y., ASSIGNOR OF ONE-HALF TO FRANCIS X. STEFFANS, OF NEW YORK, N. Y.

SURFACE-GAGE.

1,253,082.

Specification of Letters Patent.

Patented Jan. 8, 1918.

Application filed November 10, 1916. Serial No. 130,631.

To all whom it may concern:

Be it known that I, LOUIS NEUMANN, a citizen of the United States, residing at New York city, in the county of New York and 5 State of New York, have invented new and useful Improvements in Surface-Gages, of which the following is a specification.

This invention relates to surface gages and particularly to that class including a 10 stylus which is adapted to be arranged above the surface to be operated upon and to be moved thereover manually and to be actuated during such movements so as to indicate inequalities in the surface.

15 Another object of the invention is to produce a device of this character which can be readily supported from an ordinary straight edge so that the latter can be effectually advanced against the surface to be gaged 20 and the stylus adjusted on the straight edge and in the direction of the surface to be gaged at the convenience of the operator and according to the conditions of the work that is present.

25 Another object of the invention is to produce a surface gage which will include a stylus, means for effecting an approximate adjustment of the stylus with relation to the surface to be operated upon, and a second 30 means directly supporting the first means and adapted to permit very fine and delicate adjustments to be subsequently taken in the stylus.

With the above and other objects in view 35 which will appear as the nature of the invention is better understood, the same consists in the improved construction and novel arrangements of parts which will hereinafter be fully described and particularly pointed 40 out in the claims.

In the accompanying drawings, has been 45 illustrated, a single and preferred form of the invention, it being, however, understood that no limitations are necessarily made to the precise structural details therein exhibited, but that changes, alterations and modifications within the scope of the claims 50 may be resorted to when desired.

In the drawings:—

50 Figure 1 is a side view of the gage.

Fig. 2 is a plan view thereof.

Fig. 3 is a vertical section therethrough on the line 3—3 of Fig. 1.

Fig. 4 is a perspective view of the clamping screw.

Fig. 5 is a longitudinal section on line 5—5 of Fig. 1.

The device consists of a U-shaped bracket 1, having substantially parallel sides 2 and 3 and a connecting end portion 4. The device 60 is adapted to be applied to an ordinary straight edge or square and the blade of the latter is adapted to come into the space 5, between the sides 2 and 3 of the bracket 1. A clamping screw 6, is slidably mounted in 65 a channel 7, in the side 2, of said bracket 1, and said screw is provided with a head 8, which plays in the space 5, whereby it is adapted to co-act with the square or straight edge for the purpose of insuring an operative connection between the gage and said square. At one end the screw is provided with an adjusting nut 9, which is associated with the bracket 1, so that the screw can be fed with relation to the straight edge.

70 A rocker 10, is mounted upon the side 3, of the bracket and is provided with a sector 11, having an arcuate toothed surface 12, which terminates directly in advance of the rear end of said side 3, as shown. Adjacent to 75 the toothed surface are brackets 13—13, in which an operating screw 14, is swiveled. The threads of the screw intermesh with the teeth 12, of said rocker, and one end is provided with a manipulating knob 15. In this manner it is seen that the rocker can 80 be tilted at the convenience of the operator and very delicate and fine adjustments obtained.

The rocker has a forwardly rising arm 16, 90 in which a stud 17, is mounted for oscillatory movements. This stud is provided with a split end 18, through which a stylus 19 or marker is slidably mounted. The stud passes through a bushing 20, which is adapted 95 to be drawn into frictional contact with the split portion of the stud and against the extension 16, under the action of a clamping nut 21. In this manner the stylus is held against sliding movement and the 100 stud retained against oscillatory movement. By providing the stud an initial or approximate adjustment of the stylus can be obtained with relation to the work to be gaged.

The device is universally designed for the 105 purpose of gaging all surfaces and is ad-

mirably useful in setting up to the workman inconsistencies or irregularities in flat work.

What is claimed as new is:—

- 5 1. In a surface gage, the combination with a U-shaped bracket whose arms are spaced for the reception of a straight edge and one of which is channeled in its inner side, a screw longitudinally movable within said channel and with its threaded end extending through the bend of the bracket and its inner end having a head projecting into the space between said arms, and a nut threaded on said projecting end; of a rocker pivoted on said bracket and having an upstanding arm, means for mounting a stylus in said arm, and means for turning the rocker on its pivot.
- 10
- 15

2. In a surface gage, the combination with a U-shaped bracket, and means for clamping a straight edge between the arms thereof; of a rocker pivoted on said bracket and including a toothed sector at one end and an upstanding arm at the other end, a screw swiveled on the bracket and with its threads engaging the teeth of said sector, a stud mounted through said upstanding arm and split at its upper end and threaded at its lower end, a nut on said threaded end, a stylus within the split end, and a bushing surrounding said stud between its split portion and said head whereby tightening of the nut clamps the stylus, as described.

In testimony whereof I affix my signature.

LOUIS NEUMANN.
